(57) CLAIM

The ornamental design for a poseable animal figurine, as shown and described.

DESCRIPTION

FIG. 1 is a front view of a poseable animal figurine or portion thereof, showing my new design.

FIG. 2 is a top view of a poseable animal figurine or portion thereof, showing my new design.

FIG. 3 is a left side view of a poseable animal figurine or portion thereof, showing my new design.

FIG. 4 is a right side view of a poseable animal figurine or portion thereof, showing my new design.

FIG. 5 is a back view of a poseable animal figurine or portion thereof, showing my new design; and,

FIG. 6 is a bottom view of a poseable animal figurine or portion thereof, showing my new design.

The broken lines in the figures illustrate a poseable animal figurine or portion thereof that forms no portion of the claimed design.
